UNITED STATES PATENT OFFICE.

GERARD LAPIERRE, OF ST. LUDGER, QUEBEC, CANADA.

MACHINE FOR PASSING TAPE THROUGH HOOKS.

Application filed October 3, 1927. Serial No. 223,801.

This invention relates generally to labor saving machines, and has more particular reference to a novel machine for passing tapes through hooks for garters, corsets or 5 the like.

The invention has for an object the provision of a machine of the type mentioned which will automatically feed a roll of material over an inserted hook, cut the material 10 to a certain length, and pass the material through the hook. With the aid of the invention machine a person may produce a very large quantity of work in a short period of time. The necessity of manually handling 15 the material, and inserting the material through the hook, is eliminated. The operator need only feed the hooks to the machine.

The invention has for a further object, the provision of a machine of the class just briefly 20 described, which can be manufactured and sold at a reasonable cost.

For further comprehension of the invention and of the objects and advantages thereof, reference will be had to the appended 25 claims in which the various novel features of the invention are more particularly set forth, and to the following description and accompanying drawing.

Referring to the accompanying drawings, 30 forming a material part of this disclosure:

Fig. 1 is a plan view of a machine constructed according to this invention.

Fig. 2 is a side view thereof.

Fig. 3 is an end view, looking in the direction of the arrows 3-3 of Fig. 2.

Fig. 4 is a transverse sectional view, taken on the line 4-4 of Fig. 2.

Fig. 5 is a transverse sectional view, taken on the line 5-5 of Fig. 2.

Fig. 6 is an enlarged detail view of the 40 shuttle hook shown in Fig. 1.

The reference numeral 10 indicates generally vertical posts 11 longitudinal bars secured to the posts, and 12 transverse bars also 45 secured to the posts, constituting a frame for the invention machine. Bracket 13 is secured to one of the front upper longitudinal bars 11 and a roll of material 14 is rotatively arranged in the bracket. The end of the material 50 is guided beneath a material guide 15 also secured to the member 11. A shuttle guide rod 16 with a groove 17 is longitudinally arranged in the frame. A shuttle 18 is slidably engaged in groove 17 and a hook 19

55 is pivotally supported to the member 18 by

means of a pintle pin 20. An arm 21 connects the member 18 with a cord 22. One end of the cord 22 is secured to the drum 23 supported by bracket 24 to one of the transverse bars 12, and this drum is provided with 60 an internal spiral spring 25 normally turning the drum to wind the cord 22 thereon. The cord leads over idler pulleys 26 supported to cross bar 27 secured to the frame of the machine, and the end of the cord is secured to a 65 drum 28 fixed onto shaft 29 rotatably supported by arms 30 and 30' connected to the frame of the device. A bevel pinion 31 is fixed on the shaft 29 and meshes with a bevel gear 32 on a rotatably mounted shaft 33 supported by bracket 34 connected to arm 30. The shaft 33 has a pinion 35 fixed thereon, and an arcuate tooth arm 36 meshes with this 70 pinion. The arcuate tooth arm is connected at its lower end to an arm 37 pivoted at its 75 rear end to the longitudinal bar 11 as at 38.

The spring actuated drum 23 normally pulls the cord 22 so that the arm 37 is in its uppermost position, and in this position the member 18 is in an extreme right position in 80 the slot 17. A shaft 39 is rotatably arranged longitudinally in the frame of the machine, and an arm 40 with an end idler wheel 41 is engageable against the arm 37 to move this arm into lower position so that member 18 is 85 in an extreme left position in slot 17 as shown on the drawing. Spring 37' normally urges 37 upwards.

The shaft 39 is provided with a wheel 42 having a clutch arrangement 43 operable by 90 links 44 and handle lever 45. Shaft 39 is provided with a second arm 46 having an end idler roller 47 engageable with a second arm 37' pivoted at its rear to the bar 11 as at 38'. A cord 48 connects from the arm 37' to a horizontal bar 49 having one end slidably engaged in a groove 50 in post 51, the posts being supported from the frame, and the other end secured to fingers 52 connected at the top, as at 53, and pivotally arranged at the end of a bar 54 pivoted intermediate of its ends to the posts, and having its rear end connected to a tension spring 55 arranged to normally urge the front of the bar 54 upwards. 100

The shaft 39 is provided with a third arm 56 having an end idler roller 57 engageable with a third arm 37' pivoted at its rear to the bar 11, as at 38'. A cord 58 connects the arm 37' with the movable member 59 of a scissor 105

110

having a stationary member 60. Spring 61 connects the rear of the movable member 59 to the bar 11, so that normally the scissors remain open. The forward end of the scissors 5 extends across the path of motion of the material 14. The bracket 61' connected to member 11, supports a cam 62 so arranged that as the hook 19 passes towards the right it passes over the cam and in its travel to the left under 10 the cam.

The top front bar 11 is split as at 63, and adjacent the split bracket 64 is secured. This bracket has an elongated aperture 65 and pliers 66 arranged to be slidable and turnable 15 therein.

The operation of the device consists in clamping hook 67 in the pliers, moving the pliers so that the hook coincides with split 63, shown in dash-dot lines in Fig. 1. Next, 20 the handle lever 45 is moved to engage the clutch 43 and the wheel 42 should be driven by driver belt 68. Thus, shaft 39 is caused to rotate. The arm 40 moves clockwise as viewed in Fig. 3 so that roller 41 permits the 25 arm 37 to raise and the spring actuated drum draws cord 22, moving the hook 19 towards the right. The hook 19 is provided with a projecting peg 70 which passes over cam 62. As the arm 40 continues its motion it next 30 presses the arm 37 downwards, and this motion is transmitted through arcuate arm 36 and the gears to the drum 28 which draws string 22 thereon, moving the hook 19 towards the left. The peg 70 now travels beneath the cam 62 and the hook 19 is forced 35 into the end of material 14 and then draws the material across the machine, over the hook 67 aligned over split 63. The hook 19 is provided with an equilibrium spring 69 to 40 keep it in neutral position.

As the shaft 39 turns, the arm 46 with roller 47 forces the arm 37 downwards, drawing cord 48 downwards, and forcing fingers 52 to push the material 14 through the hook. 45 The arm 56 moves 37a downwards, and connected string 58 moves the scissors to cut the material. The hook 67 with a piece of material 14 looped through the holes thereof may be removed from the machine, and another hook inserted in the pliers and fed to the machine. The machine may be stopped by moving lever 45 to disengage the clutch 43.

While I have illustrated and described the preferred form, construction, and arrange-

ment of the several elements employed, it 55 will be understood that the device is nevertheless, susceptible of considerable modification therein, and I therefore reserve the right and privilege of resorting to all such changes as may be fairly embodied within the spirit 60 and scope of the invention as claimed.

Having thus described my invention, what I claim as new and desire to secure by Letters Patent of the United States is:

1. In a machine of the class described, a 65 frame, a spring operated drum arranged on one end of the frame, a cord secured to the drum, the drum normally tending to wind the cord thereon, idler pulleys arranged on the frame, a second drum fixed to a shaft 70 rotatably mounted, the said cords passing over the idlers and the end being secured to the drum, a rod connected to the frame, and arranged parallel to a portion of the cord, the 75 said rod being formed with a groove, a member slidably arranged in the groove, an arm connecting the member and cord, the last mentioned drum being arranged for rotation in one direction and then in the other so as to reciprocate the member in the groove, a 80 hook pivoted to the member, and means for causing the hook to engage tape material at one end of the stroke of said member in the groove, so as to draw the tape as the member returns to its other end of the groove. 85

2. In a machine of the class described, a 90 frame, a spring operated drum arranged thereon, a cord secured to the drum, the drum normally tending to wind the cord thereon, idler pulleys arranged on the frame, a second drum fixed to a shaft rotatively mounted, the 95 said cords passing over the idlers and the end being secured to the drum, a rod connected to the frame, and arranged parallel to a portion of the cord, a member slidably arranged on the rod, an arm connecting the member and cord, means for rotating the last mentioned drum in one direction and then in the other so as to reciprocate the member along the rod, a hook pivoted to the 100 member and means for causing the hook to engage tape material at one end of the stroke of said member along the rod, so as to draw the tape as the member returns to its other end of the rod. 105

In testimony whereof I have affixed my signature.

GERARD LAPIERRE.
